UNITED STATES PATENT OFFICE.

WILLIAM H. NOELTING, OF EVANSVILLE, INDIANA, ASSIGNOR TO FAULTLESS CASTER COMPANY, OF EVANSVILLE, INDIANA, A CORPORATION.

FURNITURE LEG SLIDE.

Application filed August 15, 1925. Serial No. 50,429.

This invention relates to what is commonly called a furniture slide formed from a single piece of sheet metal.

The chief object of the invention is to 5 form a slide of the foregoing character so that it will have certain structural characteristics heretofore not found in the devices of this type.

The chief feature of the invention consists 10 in the formation of the several anchorage portions with a beveled or tapered face, and a central bearing portion of increased thickness during the blanking of the slide or immediately prior to the formation 15 of the blank into cup form.

Another feature of the invention consists 20 in the provision of a plurality of prongs arranged in spaced relation about the external periphery of the slide and the provision of a plurality of intermediately positioned wedges, the latter having a relatively low height and a relatively wide base compared to the height and base width of the 25 prong.

Another feature of the invention consists 30 in the offsetting laterally of the prongs and preferably the curvature of said prongs whether offset or otherwise as pointed out hereinafter.

The full nature of the invention will be 35 understood from the accompanying drawings and the following description and claims:

In the drawings Fig. 1 is a top plan view 40 of a slide blank showing the outline thereof. Fig. 2 is an edge elevation of one form of blank showing the swedging or tapering of the prong. Fig. 3 is a similar view of a different formation of the prong. Fig. 4 is a similar view of another formation of the 45 prong, this formation being positioned intermediate that shown in Figs. 2 and 3. Fig. 5 is a side elevational view of the simplest type of slide embodying the invention. Fig. 6 is a central sectional view thereof. Fig. 7 is a similar view of a modified form of the 50 invention. Fig. 8 is a view similar to Figs. 6 and 7 and of a still further modified form of the invention. Fig. 9 is a top plan view 55 of a slide, the prongs of which are formed as shown in Fig. 2. Fig. 10 is a top plan view similar to Fig. 9 but of a modified form of the invention wherein the prongs are offset laterally and inwardly with respect to the

55 marginal portion of the slide and are curved with their concave curvatures outwardly positioned. Fig. 11 is a top plan view showing a further modification. Fig. 12 is a central sectional view through one of the 60 prongs shown in Fig. 11 and a portion of the slide and is taken on line 12-12 of Fig. 11. Fig. 13 is a view similar to Fig. 11 but of a modified form of slide wherein the off-setting of the prong extends into and substantially through the marginal zone of the slide. Fig. 14 is a view similar to Fig. 12 and is taken on line 14-14 of Fig. 13. Fig. 15 is a top plan view of a modified form of the invention, wherein the prong is corrugated. Fig. 16 is a similar view of a modified form 70 of Fig. 15, wherein the prong is offset laterally and outwardly with respect to the marginal zone. Fig. 17 is a top plan view of a modified form of the invention and the preferred form, to wit, which all the claims 75 read upon.

In the drawings 10 indicates a substantially flat bearing zone, 11 an intermediate zone and 12 a marginal zone. A plurality 80 of prongs, and herein three are illustrated, are indicated in the several figures by the numeral 14, and interposed between said prongs and also integral with the marginal zone are wedges 15. The wedges 15 have a relatively low height and a relatively wide base, while the prongs 14 have a relatively high height and a relatively narrow base. The foregoing constitutes the simplest form 85 of the invention and as will be observed from Figs. 1 and 5, said prongs and wedges are substantially triangular in outline.

In Fig. 2 an edge view of the blank adjacent the prong is illustrated and shows the formation of the taper of the prong by the swedging or flattening of the face 14^a, the face 14^b in this form being continuous with the exterior of the marginal zone. In Fig. 3 a reverse form of prong is illustrated and in this form the flat face 114^a is continuous 90 with the interior surface of the marginal zone 12, while the inclined face 114^b is inclined to the exterior of the marginal zone. In Fig. 4 the marginal zone 12 supports the prong 14 which has its faces 214^a and 214^b shown inclined to the exterior and interior 95 surfaces of the marginal zone 12. The foregoing arrangement, to wit, with the marginal zone continued upwardly throughout 100 105

the prong, is shown clearly in Fig. 9 and corresponds to that form of the invention shown in Fig. 2.

As shown clearly in the several figures, particularly Figs. 6 to 8 and 12 and 14, the central bearing zone 10 is of considerably greater thickness than the intermediate zone 11 and the marginal zone 12. This increased thickness not only acts as a stiffener, but also provides increased metal for wear, thereby insuring a longer life in a slide of this character than has heretofore been obtainable. This increased thickness is formed by swaging or otherwise and is produced in the blank prior to its final formation in cup design, shown in Fig. 5.

The wedges 15 are herein illustrated as provided with their exterior faces a continuation of the marginal zone, thus being comparable to the type of construction shown in Fig. 2 for the prong. The prongs and the wedges are both herein shown triangular in outline. As shown clearly in Figs. 5 and 6, the inclined edges of the bases and prongs have common intersections coincident with the marginal zone. As shown in Fig. 7, said intersections are formed by a curved notch or fillet arrangement indicated by the numeral 116. Also as indicated in Fig. 8 the wedge, while substantially triangular in outline, is curved as at 115 and thus is of spherical triangle character.

In Figs. 11 to 16 inclusive, modified forms of the invention are illustrated and the several figures show a laterally offset prong variously arranged. In Figs. 11 and 12 the prong 314 is shown offset laterally and outwardly with respect to the marginal zone and is integral therewith. In Figs. 13 and 14 the prong 414 is offset laterally and outwardly from the marginal zone, but in this form of the invention the portion 412 of the marginal zone is also offset outwardly and laterally so that the prong extends upwardly from said outward offset marginal portion 412.

In Fig. 15 there is illustrated a further modified form of the invention, wherein the prong is not only of a curved nature such as shown in Figs. 11 to 14 inclusive, but this prong 514 is provided with a corrugated outline, having an exterior surface 514^c and an interior surface 514^d. In Fig. 16 a combination of the forms shown in Figs. 14 and 15 is illustrated, and in this form the corrugated prong 614 is shown provided with the exterior surface 614^c and the interior surface 614^d. In this form of the invention, however, the entire prong is offset laterally and

outwardly by the portion 612 and in this respect is similar to the form of the invention shown in Figs. 13 and 14.

The specific form of the invention elected is a combination of the several variations or modifications illustrated herein in the several figures and comprises a central bearing zone of increased thickness, an intermediate zone, a marginal zone having outwardly projecting lateral portions, corrugated tapered triangularly outlined prongs extending upwardly therefrom, and tapered triangularly outlined wedges interposed therebetween and integral with the marginal zone, said prongs and wedges having notched or filleted connections.

Herein the aforesaid specific form upon which all the claims read and as described immediately preceding is illustrated in Fig. 17 in which the like parts are similarly numbered, all numerals being of the seven hundred series.

The invention claimed is:

1. In a sheet metal slide, the combination of a marginal zone, a substantially flat central bearing zone of greater thickness than the marginal zone connected thereto, a plurality of tapered prongs, and a similar number of tapered wedges interposed between said prongs.

2. In a sheet metal slide, the combination of a marginal zone, and a plurality of prongs integral therewith and offset laterally and outwardly from said marginal zone and including a laterally and outwardly offset portion of the marginal zone.

3. In a sheet metal slide the combination of a marginal zone, and a plurality of prongs each having a greater width than thickness and integral with said zone, each having both of its wider faces inclined thereto and towards each other for tapering purposes.

4. In a sheet metal slide, a marginal zone, and a plurality of triangular wedges each having a base greater than its height and integral with said zone, each having one of its faces inclined thereto for tapering purposes.

5. In a sheet metal slide, the combination of a marginal zone, a plurality of prongs integral with said zone, and a plurality of wedges also integral therewith and interposed between said prongs, said zone having an interrupting notch between each prong and wedge.

In witness whereof, I have hereunto affixed my signature.

WILLIAM H. NOELTING.
